COMBINED MOTORCYCLE SAFETY BAR AND FOOT RESTS

Kenneth E. Higginbotham, 12236 SE. 200th,
Kent, Wash. 98031

Filed June 15, 1973, Ser. No. 370,306

Term of patent 14 years

Int. Cl. D12—II

U.S. Cl. D12—114

FIG. 1 is a rear elevational view of a combined motorcycle safety bar and foot rests for attachment to a single tube frame of a motorcycle showing my new design;

FIGS. 2 and 3 are respective side elevational views thereof;

FIG. 4 is a front elevational view thereof;

FIG. 5 is a top plan view thereof;

FIG. 6 is a bottom plan view thereof; and

FIG. 7 is a rear perspective view thereof.

I claim:

The ornamental design for a combined motorcycle safety bar and foot rests, as shown.
